(57) **CLAIM**

I claim the ornamental design for an interactive toy, as shown and described.

DESCRIPTION

FIG. 1 is an upper left front perspective view of an interactive toy showing my new design, with a base shown in dashed lines for illustrative purposes only and forms no part of the claimed design;

FIG. 2 is an upper right rear perspective view thereof;

FIG. 3 is a lower left front perspective view thereof;

FIG. 4 is a front elevational view thereof;

FIG. 5 is a right side elevational view thereof;

FIG. 6 is a rear elevational view thereof;

FIG. 7 is a left side elevational view thereof;

FIG. 8 is a top plan view thereof; and,

FIG. 9 is a bottom plan view thereof.

1 Claim, 9 Drawing Sheets
